UNITED STATES PATENT OFFICE

137,721

DESIGN FOR A COMBINATION COMB AND FINGERNAIL FILE

Robert C. Torian, Beehive, Mont.

Application June 8, 1943, Serial No. 110,402

Term of patent 14 years

(Cl. D86—8)

To all whom it may concern:

Be it known that I, Robert C. Torian, a citizen of the United States, residing at Beehive, in the county of Stillwater and State of Montana, have invented a new, original, and ornamental Design for a Combination Comb and Fingernail File, of which the following is a specification, reference being had to the accompanying drawing, forming part thereof.

Figure 1 is a side elevation of a combination comb and fingernail file showing my new design.

Figure 2 is a horizontal cross sectional view

taken thru the file portion of the comb, substantially on the line 2—2 of Figure 1.

Figure 3 is an end elevation of the comb and file looking in the direction of the point end of the file.

Figure 4 is a cross sectional view taken substantially on the line 4—4 of Figure 1.

I claim:

The ornamental design for a combination comb and fingernail file, substantially as shown.

ROBERT C. TORIAN.
